Atty.

UNITED STATES PATENT OFFICE.

MATHEW SOENS, OF STREATOR, ILLINOIS.

SOLE-STITCHING MACHINE.

1,215,733.

Specification of Letters Patent. Patented Feb. 13, 1917.

Application filed March 28, 1916. Serial No. 87,168.

To all whom it may concern:

Be it known that I, MATHEW SOENS, a citizen of the United States, residing at Streator, in the county of La Salle and State of Illinois, have invented certain new and useful Improvements in Sole-Stitching Machines, of which the following is a specification.

The present invention relates to machines 10 of the Gritzner type, for stitching shoe soles.

The objects of the invention are, to provide means for actuating this type of stitching machine by application of power, as 15 differentiated from a hand operation; and to carry out this power operating principle in a manner whereby the mechanism of the present Gritzner style of machine is maintained, and whereby the machine can be 20 transformed into a power operated one by very slight changes in the present hand operated construction.

The invention further consists in the features of construction and combination of 25 parts hereinafter described and claimed.

In the drawings:

Figure 1 is a side elevation of a shoe stitcher of the Gritzner type, with the mechanism of the present invention applied 30 thereto;

Fig. 2, a plan view of said machine, with the mechanism of the present invention applied thereto; and

Fig. 3, a front view of the mechanism of 35 the present invention, and also showing the reciprocating operating member of the stitching machine and the method of connecting such operating member to a power driven actuating member.

40 In the art to which the present invention relates, there is at present on the market a hand operated sole stitcher, known as the Gritzner, which is a very cheap and simple machine, but which is open to the serious 45 objection of being difficult to manipulate by a hand operated method. I have found that by a very simple means I can operate this type of machine with a power mechanism, and this without disturbing in any way the 50 arrangement or construction of the operating parts of the present Gritzner machine.

55 Referring now to the drawings, the stitcher is designated by the general numeral 4. This stitcher comprises a reciprocating operating member 5, actuating a pivoted arm 6, which in turn operates a

needle 7. A spool of thread 8 is attached to the machine and is fed forward by the operation of the needle. A tension mechanism 9 is provided for this thread. The entire 49 mechanism is supported on a base plate 10, and the operating member 5 travels within a casing 11, which serves as a guide therefor. In operating the machine, the shoe is placed against a backing member 12, and 55 by suitable means is turned a predetermined degree at each operation of the stitching member.

It is not believed necessary to enter into further detailed description of the construction or operation of the sole-stitching mechanism, since, as stated, this is of the type now well known to the trade as the Gritzner sole stitcher. This machine, as now on the market, is operated by hand power, the 75 operator grasping a handle or grip 13 in one hand and holding the shoe in the other. This is unhandy and results in great difficulty in properly carrying on the work, and I have found that by a very slight 80 alteration to the present machine, I can operate it by foot or other power, thus leaving both hands free for manipulating the shoe, and resulting in a substantial advantage in both the speed of operation and character 85 of the work produced.

To carry this out, I form a slot 14 in the upper plate 15 of the casing 11, and I attach a pin 16 to the operating member 5, so that it extends upwardly therefrom and 90 projects through the slot 14 (see Fig. 3). The forming of this slot and the insertion of the pin 16 constitute the only changes that are necessitated in the present Gritzner machine to operate it by foot or other 95 power, as differentiated from hand power; and the main point in the invention lies in the way which I have discovered for converting this machine from a hand operated type to a foot or other power operated type. 100

To the pin 16 I attach an arm 17, which in turn is connected to a stud 18 on a fly-wheel or disk 19. This latter constitutes a power driven actuating member for the mechanism, and in the construction shown is actuated by a bolt 20 extending from a pulley 21, which is operated by means of a foot treadle 22 and a connecting arm 23, although the precise means of operating the power driven actuating member may be varied, provided it is maintained within the 110 limitations of the appended claim. The

foregoing, however, is a cheap and practical method for operating this power driven actuating member 19.

It will be obvious from the foregoing description that, as the treadle 22 is rocked by the foot of the operator, it will drive the belt 20, rotating the flywheel or disk 19, which will impart a reciprocating movement to the link 17 and move the reciprocating member 5 back and forth, thus operating the machine, and that by so operating it, the user has both hands free for holding and turning the shoe. It is also apparent that, so far as the mechanism for operating the needle and for placing tension on the thread are concerned, these are not altered or changed in the least by providing the present improvement. In fact, the machine remains identical, with the exception that by a simple addition it is oper-

ated by power other than hand, thus expediting the use of the machine.

I claim:

A sole stitcher of the Gritzner type, comprising a table, a horizontally reciprocating operating member above the table, thread feeding mechanism and needle mechanism actuated by said operating member, a casing carried by the table in which said operating member moves, said casing having a slot formed therein, said slot extending parallel with the direction of movement of the reciprocating member, a pin connected to the operating member and extending through said slot to a point beyond the outer wall of the casing, a power driven member, and a connection between said pin and power driven member, substantially as described.

MATHEW SOENS.
